UNITED STATES PATENT OFFICE.

GEORGE SINGLETON, OF DOVER, NEW JERSEY.

HORSESHOE.

SPECIFICATION forming part of Letters Patent No. 588,022, dated August 10, 1897.

Application filed August 13, 1896. Serial No. 602,659. (No model.)

To all whom it may concern:

Be it known that I, GEORGE SINGLETON, a citizen of the United States, and a resident of Dover, in the county of Morris and State of New Jersey, have invented certain new and useful Improvements in Horseshoes; and I do hereby declare that the following is a full, clear, and exact description of the invention, which will enable others skilled in the art to which it appertains to make and use the same, reference being had to the accompanying drawings, which form a part of this specification.

My invention relates to horseshoes and detachable toe and heel calks therefor; and its object is to provide an improved construction whereby the calks may be readily removed and replaced when desired without removing the shoe or the nails which secure it to the hoof.

The invention consists in the combination, with a horseshoe having downwardly-depend- ing lugs on the under side formed with dove-tailed grooves extending from one end to near the other end and with alined opposite slots near the open end, of a calk having a dove-tailed rib on its upper side engaging with said groove and a key passing through said slots and abutting against the end of the rib, as hereinafter fully described and claimed.

In the accompanying drawings, Figure 1 is a central longitudinal section of a horseshoe constructed in accordance with my invention. Fig. 2 is a bottom view of the shoe, the calks being removed. Fig. 3 is a perspective view of one of the heel-calks detached. Fig. 4 is a detail cross-sectional view of one of the ends of the shoe.

In the said drawings the numeral 1 designates the shoe, provided on the under side with the usual crease or channel 2 and formed with nail-holes 3.

At each end and at the toe the shoe is formed on the under side with a downwardly-depend- ing lug 4. These lugs are similar in all es- sential respects and are formed with dove-tailed grooves 5, extending from one end to near the opposite end, forming, as it were, opposite dovetailed flanges connected to- gether at one end. Near the upper ends the lugs are formed with opposite alined slots or

recesses 6 to receive a key hereinafter de- scribed.

The numeral 7 designates the calks, which may be sharpened or not, as desired, each 55 formed on its upper sides with a dovetailed rib 8, corresponding with the groove in the lugs and somewhat shorter than the calks themselves. The numeral 9 designates a key adapted to engage with said slots in the lugs. 60

In practice the calks are connected with the lugs by sliding the ribs into the grooves, the front ends of the ribs abutting against the closed ends of the lugs. The keys are then driven into or through the slots and bearing 65 against the outer ends of the ribs will securely hold the calks in place and prevent acciden- tal detachment or loosening of the same from the shoe.

To remove the calks, the keys are driven 70 out, when the calks can be forced out of the grooves by a blow from a hammer or other tool. It will thus be seen that the calks do not in any manner interfere with the nails which hold the shoe to the hoof, so that they 75 can be removed and replaced without remov- ing the shoe or any of the nails which hold it in place.

Having thus fully described my invention, what I claim is— 80

The combination with a horseshoe having lugs on the under side provided with dove- tailed grooves forming tapering flanges con- nected together at the contracted end form- 85 ing a solid portion, and said flanges discon- nected at the expanded or large ends forming a passage-way for the ribs of the calks, and the flanges near said open end provided with opposite slots, of the calks having dovetailed ribs on their upper or inner sides engaging 90 with said grooves and one end abutting against the solid connected ends of said flanges, and the keys driven through said slots and bearing against the opposite ends of said ribs, substantially as described. 95

In testimony that I claim the foregoing as my own I have hereunto affixed my signature in presence of two witnesses.

GEORGE SINGLETON.
